UNITED STATES PATENT OFFICE.

RAYMOND N. EHRHART, OF EDGEWOOD PARK, PENNSYLVANIA, ASSIGNOR TO WESTINGHOUSE ELECTRIC & MANUFACTURING CO., A CORPORATION OF PENNSYLVANIA.

CONDENSER AND AIR-PUMP APPARATUS.

Application filed November 21, 1917. Serial No. 203,263.

To all whom it may concern:

Be it known that I, RAYMOND N. EHRHART, a citizen of the United States, and a resident of Edgewood Park, in the county of Allegheny and State of Pennsylvania, have made a new and useful Invention in Condenser and Air-Pump Apparatus, of which the following is a specification.

This invention relates to condenser installations and has for an object to produce a new and improved arrangement of water connections to the air pump which withdraws air and other non-condensable gases and vapors from the condenser.

10 A further object is to produce a new and improved arrangement of air pump water connections, which is well adapted to be employed where the level of the water at the source of supply varies considerably, and 20 which prevents variations in the level of the water from affecting the operation of the air pump.

25 A further object is to produce an air pump water connection arrangement in which the air pump is independent of variations in pressure or level of the water at the source of supply.

These and other objects are attained by 30 means of the condenser and air pump arrangement embodying the features herein described and illustrated in the drawings accompanying and forming a part hereof.

Hydraulic air pumps are frequently employed for exhausting condensers and are 35 ordinarily arranged so as to discharge into the cold well or hot well of the plant in which they are employed. This arrangement is not practical in plants where the level of the water at the source of supply is 40 variable and sometimes rises to a level above the air pump. My invention contemplates an arrangement of water connections in which the pump is independent of variations in level of the water at the source of supply. I preferably arrange the pump so 45 as to draw entraining water from an isolated tank and to discharge it with the entrained air and other fluids into the same tank. I also preferably provide means for 50 automatically changing the water in the tank so that the temperature of the water drawn into the pump will not exceed a safe or determined temperature.

The drawing is a diagrammatic sectional view of a condenser and air pump installa-

tion embodying the features of my invention.

In the drawing I have illustrated a surface condenser 5 which is supplied with cooling water by means of a circulating pump 6. 60 As shown, the pump 6 draws water from a cold well 7, which communicates with a source of supply 8 by means of a tunnel 9. The pump 6 forces the water through the tubes of the condenser 5 in the usual manner. A hydraulic air pump 10 is shown as connected to the condenser by means of a conduit 11 and is adapted to withdraw air and non-condensable gases and vapors from the condenser. In some installations this 70 pump would be connected up so as to discharge into the cold well 7, but as shown, the water level in the source of supply 8 is considerably above the pump 10 and consequently this cannot be done without flooding 75 the pump.

In the illustrated embodiment of my invention, the air pump 10 is adapted to discharge into an isolated tank 12, which is placed at any convenient level and which is 80 open to the atmosphere so as to permit the escape of the non-condensable gases and vapors withdrawn from the condenser. The suction line 13 of the pump 10 also extends into the tank 12 and is adapted to deliver 85 water to the pump to be employed in entraining the fluids withdrawn from the condenser 5.

It is necessary to supply makeup water to the tank 12 in order to make up for the water 90 lost by evaporation, and to prevent a prohibitive rise of temperature of the water in the tank. This makeup water is preferably withdrawn from the discharge side of the circulating pump 6 by means of a conduit 14 and, as shown, is delivered directly to the suction line 13 of the pump 10. A valve 15, controlled by a float 15^a, is provided for controlling the delivery of makeup water so 95 that a substantially constant level of water 100 is maintained in the tank 12.

I have also shown a pump 16 for withdrawing water from the tank 12 and for delivering it to any convenient place. As shown, it is connected to the tank 12 by 105 means of a conduit 17 and to the circulating water system of the condenser by means of a conduit 18. This arrangement provides for the circulation of water through the tank 12 at such a rate as to prevent the 110

temperature of the water from rising above a safe or desirable temperature.

It is evident that the level of the water in the tank 12 is entirely independent of the 5 level of the water in the source of supply 8 because the float controlled valve 15 maintains the level in the tank constant. Furthermore, the water in the tank 12 is preferably renewed at such a rate that the temperature of the water may be maintained at 10 the most advantageous degree. With the arrangement shown, the installation has the further advantage that the water withdrawn from the circulating system for use in the 15 air pump 10 is returned again to the circulating system by the pump 16 so as to ultimately be circulated through the condenser with the rest of the circulating water.

While I have illustrated and described 20 but one embodiment of my invention, it will be apparent to those skilled in the art that various changes, modifications, substitutions, additions and omissions may be made in the apparatus illustrated without departing 25 from the spirit and scope of the invention as set forth by the appended claims.

What I claim is:

1. In a condenser installation, a condenser 30 having a cooling water circulating system, a hydraulic air pump for exhausting the condenser, an isolated receptacle into which the air pump discharges, a conduit for delivering entrained liquid to the air pump from the receptacle, means for delivering liquid from the water circulating system into the conduit, and means for maintaining a predetermined amount of liquid in the receptacle.

2. In a condenser installation, a condenser 40 having a cooling water circulating system, a hydraulic air pump for exhausting the condenser, a fluid receptacle into which the air pump discharges, a conduit for delivering entrained liquid to the air pump from the receptacle, means for delivering liquid from the water circulating system into the conduit, means for controlling the delivery of said liquid so as to maintain a predetermined amount of liquid in the receptacle, and means for separately withdrawing liquid from the upper portion of the receptacle at such a rate that the incoming liquid maintains the temperature of the contents of the receptacle below a predetermined 50 temperature.

3. In a condenser installation, a condenser, a hydraulic air pump for exhausting the condenser, means for circulating cooling water through the condenser, an isolated 60 tank into which the air pump discharges, a conduit for delivering entraining water from the tank to the pump, means for delivering water from the circulating means into the conduit, and means for regulating the delivery of water to the conduit so as to pre-

vent the contents of the tank from being overheated.

4. In a condenser installation, a condenser, a hydraulic air pump for exhausting the condenser, means for circulating cooling water through the condenser, a tank into which the air pump discharges, a conduit for delivering entraining water from the tank to the pump, means for delivering water from the circulating means into the conduit, means for regulating the delivery of water through said means so as to maintain a substantially constant level of water in the upper portion of the tank, and means for withdrawing water from the tank. 80

5. In a condenser installation, a condenser, a hydraulic air pump for exhausting the condenser, means for circulating cooling water through the condenser, a tank into which the air pump discharges, a conduit for delivering entraining water from the tank to the pump, means for delivering water from the circulating means into the conduit, means for regulating the delivery of water through said means so as to maintain a substantially constant level of water in the tank, and means for withdrawing water from the tank and for delivering it back to the circulating means. 85

6. The combination with a condenser having a cooling water circulating system and a fluid actuated pump for exhausting the condenser, of an open tank receiving water under pressure from the circulating system and receiving the fluids discharged by the said pump, means for maintaining the fluid in the tank at a determined level; and means for withdrawing water from the tank adjacent the surface thereof, whereby water at a maximum temperature is removed. 95

7. In a condenser installation, a condenser having a cooling water circulating system, a hydraulic air pump for withdrawing air from the condenser, a tank into which the air pump discharges, a pipe leading from the cooling water circulating system into the intake of the pump for delivering entraining water thereto and an overflow connecting the upper portion of the tank with the circulating system. 110

8. In a condenser installation, a condenser, means including a pump for circulating cooling fluid therethrough, a hydraulic pump for exhausting the condenser, a receptacle to receive the pump discharge and to hold a supply of fluid for the pump, a pipe between the receptacle and the cooling fluid circulating means whereby fluid may be discharged from the upper portion of the receptacle to the circulating means, a circulating pump in said pipe, a connection between the circulating means and the receptacle for supplying fluid from the circulating means to the receptacle, and means for controlling the passage of fluid through the last named connec- 125

tion responsive to the level of fluid within the receptacle.

9. In a condenser installation, a condenser, a cooling system for the condenser including a pump, a hydraulic pump for exhausting the condenser, a receptacle to receive the hydraulic pump discharge and to hold a supply of fluid for the hydraulic pump, a pipe between the receptacle and the cooling system adapted to discharge fluid from the upper portion of the receptacle to the cooling system between the pump and condenser,

an independently operated pump in said pipe and a connection between the receptacle and the cooling system between the pump and the condenser adapted to supply fluid to the receptacle from the cooling system.

In testimony whereof, I have hereunto subscribed my name this 19th day of November, 1917.

RAYMOND N. EHRHART.

Witness:

C. W. McGHEE.

Certificate of Correction.

It is hereby certified that in Letters Patent No. 1,466,042, granted August 28, 1923, upon the application of Raymond N. Ehrhart, of Edgewood Park, Pennsylvania, for an improvement in "Condenser and Air-Pump Apparatus," errors appear in the printed specification requiring correction as follows: Page 2, line 79, claim 4, strike out the words "the upper portion of", and line 80, before the word "tank" insert the words *upper portion of the*; and that the said Letters Patent should be read with these corrections therein that the same may conform to the record of the case in the Patent Office.

Signed and sealed this 9th day of October, A. D., 1923.

[SEAL.]

WM. A. KINNAN,
Acting Commissioner of Patents.
